(57) **CLAIM**

The ornamental design for a pillow cover, as shown and described.

DESCRIPTION

1. Pillow cover

1.1 : Perspective

1.2 : Front

1.3 : Back

1.4 : Left

1.5 : Right

1.6 : Top

1.7 : Bottom

The broken line portions are shown to illustrate environment and seam and form no part of the claimed design; the dashed-dotted broken lines shown in fig. 1.1 and figs. 1.6 to 1.7 depict a boundary between the claimed portion and the unclaimed portion and form no part of the claimed design.
